UNITED STATES PATENT OFFICE.

HARRY O. RUGH, OF SANDWICH, ILLINOIS.

SELECTIVE SIGNALING SYSTEM.

No. 899,564.

Specification of Letters Patent.

Patented Sept. 29, 1908.

Application filed December 9, 1907. Serial No. 405,659.

To all whom it may concern:

Be it known that I, HARRY O. RUGH, citizen of the United States, residing at Sandwich, in the county of DeKalb and State of Illinois, have invented a certain new and useful Improvement in Selective Signaling Systems, of which the following is a full, clear, concise, and exact description, reference being had to the accompanying drawings, forming a part of this specification.

My invention relates to selective circuit or signaling systems, and has for its object the provision of an improved signaling or circuit selective apparatus and an improved circuit arrangement for selective signaling purposes.

I will explain my invention fully by reference to the accompanying drawing, showing the preferred embodiment thereof, in which—

Figure 1 is a diagram indicating generally a circuit arrangement entering into the system of my invention. Fig. 2 indicates selective signaling apparatus in diagrammatic form and located at one of several signaling stations upon a signaling circuit.

Like parts are indicated by similar characters of reference in both figures.

My invention is primarily designed for use in association with telegraph circuits where telephone outfits are also located, the invention enabling a master operator or despatcher to operate the signal of a selected station, so that the operator or the one who is to respond at the signaled station may understand that he is to put himself into communication with another party or parties.

My invention finds an important commercial use in connection with those telegraphic systems that also employ telephones, so that during the busier hours of the day the telegraphic outfits at the various stations may be manned by competent telegraphers, whereas during the quieter hours the telegraph operators may be relieved of duty, to be replaced by those who are to use the telephones and who, consequently, need not be skilled in telegraphy. While my invention has this important commercial advantage, I do not wish to be limited to this use of the invention, nor do I wish to be limited to other uses of my invention, for it is obvious that the system and apparatus of my invention may have other utilities; for example, the signaling devices may be employed at telegraph stations having no telephones and where the telegraph operators have other

duties, the system of my invention enabling such operators to be called by loud sounding signals when they are to attend to their telegraph instruments. The system and apparatus of my invention is also adaptable for other uses which have not been named.

In Fig. 1 I have illustrated a conductor *a* uniting a number of telephone stations *a*¹ and have illustrated another conductor *b* uniting a number of telegraph stations *b*¹, *b*², each telephone station being collocated with a telegraph station. The station *b*¹ may, for example, be considered as a calling station, such as a train despatcher's station, and while it is shown at the end of the conductor *b*, I do not wish to be limited to its association with this conductor for the purpose of operating the calling signals at the telephone and telegraph stations. The station *b*¹ is shown as being equipped with the usual telegraphic outfit including a sending key *e*, a line relay *e*¹, and a sounding outfit *e*². Each of the other stations *b*² is equipped with similar telegraphic apparatus. At the calling station I have illustrated the telegraph battery *f*, each pole of which is connected with two terminals, the terminals *g* and *h* being normally in connection with contact arms *g*¹ and *h*¹. The alternate contacts *g*² and *h*² are respectively connected with the same poles of the battery that are connected with the normal contacts *g* and *h*, said alternate contacts being adapted for engagement with the switch arms *g*¹ and *h*¹ when said switch arms are moved to the right. When the arms *g*¹ and *h*¹ are in their normal positions, current from the battery *f* is impressed upon the line *b* in one direction. When said arms *g*¹ and *h*¹ are in their alternate position, current from the battery *f* is impressed upon the line *b* in the reverse direction. The battery *f* in its normal circuit relation with the line *b* is adapted to be used as the telegraphing battery, for it is normally included in a grounded circuit with said line. I have shown at the sending station *b*¹, a magnet *i* for shifting the arms *g*¹ and *h*¹ from their normal to their alternate positions, said operating magnet *i* being included in a local circuit with a battery *i*¹ and a calling key *i*². I have not indicated at the other substations *b*² the details of the telegraphic outfits there located, it being understood that the line relays at these other substations are in series with the telegraph line and that they are associated with sounding outfits and telegraph

keys, as indicated in connection with the station b^1 . I, therefore, deem it sufficient to indicate by circles at the stations b^2 the apparatus there located. The apparatus at one of the substations b^2 is shown in full in Fig. 2, where the line relay e^1 is included in series with the telegraph line b and is shown in association with a sounder circuit e^2 , as is well understood. The calling key e is also shown in Fig. 2 in series with the line, as is well understood. At the substation b^2 indicated in Fig. 2, I have also shown a polarized relay k in series with the line b having an arm l placed at the right when the sending key i^2 is in its normal released position, in which position the switch arms $g^1 h^1$ at the calling station occupy their left-hand position. The switch arm l is permanently connected with one terminal of a battery m , while the contact l^1 of the switch arm l is connected with the other terminal of the battery m . Whenever the calling key i^2 at the calling station is depressed, the battery current impressed upon the line b is reversed and the arms l at all of the telegraph stations are moved to the left, whereby a circuit is closed at each telegraph station which includes the arm l , the contact l^1 , the winding of an operating electro-magnet n , the battery m , and a magnet o . Each time the arms l are moved to the left, which occurs upon each depression of the calling key i^2 , the magnet n is energized to move in a clockwise direction, a bell crank lever device p , pivoted at its elbow, which bell crank lever device has pivotally supported upon its upper arm an actuating pawl p^1 adapted to engage with the teeth upon the periphery of a switching quadrant or element p^2 having a stationary pivotal point. Said quadrant is of metal and is connected with one pole of the battery m and carries a brush m^1 of a size just sufficient to permit of the electrical connection of the quadrant p^2 with a contact button p^3 when said element p^2 is brought into selected position.

The contact buttons p^3 at the different stations occupy varying positions with respect to the brush m^1 , so that but one signaling circuit among all of the stations is established at a time. Each time the levers p are operated, the actuating pawls p^1 cause the quadrants to rotate in clockwise directions, a step, each step accompanying a depression of the calling key i^2 . Holding pawls p^4 are provided at the different stations to retain the switching quadrants in the positions to which they have been stepped. When the quadrants have been moved a number of steps that will bring the quadrant at the selected station into circuit relation with the signal button p^3 thereat, the calling key i^2 is maintained in its actuated position, in order to maintain the magnet n energized and in order to remove a weight q from engagement

with one end of an intermediately pivoted lever q^1 , whereby the other end of said lever is permitted to descend, owing to the preponderance of weight it possesses over the first end of the lever, the weight q , when in engagement with the lever q^1 , normally overcoming this preponderance of weight. The right-hand and heavier end of the lever q^1 is, however, but slightly heavier than the left-hand end of said lever, so that when the weight q is removed from engagement with the lever q^1 , the heavier end of said lever descends but slowly. The object of having the right-hand end of the lever q^1 but slightly heavier than the left-hand end is to prevent the lever q^1 from materially moving between the short intervals that occur between the depressions of the key i^2 in selecting a station to be signaled. When, however, the station which is to be signaled has been selected, the key i^2 is maintained in a depressed position, whereupon the lever p lifts the weight q from the lever q^1 at each station, thereby permitting the heavier end of the lever q^1 at each station to descend. The lever q^1 in descending, closes the contacts r that are included in circuit with a signal device r^1 , such as a bell, at the selected station only, this signaling circuit being traced from the upper pole of the battery m through the contacts r , the signal device r^1 , the contact button p^3 at the selected station (the contact buttons p^3 at the other stations being in open circuit), the switching quadrant p^2 , to the lower pole of the battery m . In order to insure engagement between the contacts r , I also include in the circuit just traced, a magnet o , into whose magnetic field the heavier end of the lever q^1 descends, the magnet, by its attraction upon the lever q^1 forcing firm engagement between the contacts r . Thus a continued depression of the calling key i^2 maintains the signaling circuit closed and removes the weights q at all of the telegraph stations from the levers q^1 thereat, and effects the operation of the signaling device r^1 at only the selected station, inasmuch as the signaling circuit is closed only at the selected station.

In order that the apparatus may be restored to normal, the holding pawl p^4 should be withdrawn from engagement with the teeth of the ratchet p^2 , to which end I desirably connect the holding pawl p^4 with the armature of an electro-magnet s . The electro-magnet s at each station is included in circuit with the contacts r and with the battery m when the contacts r at the various stations are brought together. The magnets s are thereupon energized to withdraw the holding pawls p^4 preparatory to permitting the retractile springs s^1 at the various stations to restore the element p^2 . However, when the magnets s are thus energized by the closure of the contacts r , the magnets s re-

main energized during the continued depression of the calling key i^2 , so that the restoration of the selective devices at the various stations to normal does not occur until the levers p are released by the magnets n , whereupon the actuating pawls p^1 drop to their normal positions.

The weight q is in the form of a vertically reciprocating rod whose lower end is adapted to be engaged by the upwardly moving end of the bell crank lever p . I do not wish to be limited, however, to the shape of the weight q , nor to the precise way in which it is permitted to engage the lever q^1 and is caused to be disengaged from said lever.

In the embodiment of the invention herein shown, the telephone stations are indicated as being connected with a conductor a which is not in conductive connection with the conductor b , but I do not wish to be limited, of course, to a system in which the telephone circuits and the telegraph circuits are upon distinct wires, nor, as hitherto stated, do I wish to be limited to the use to which my improved selective signaling system is here put.

It is obvious that changes may readily be made in the preferred embodiment of the invention herein illustrated, without departing from the spirit of the invention, and I do not, therefore, wish to be limited to the precise form of the invention illustrated, but,

Having thus described my invention, I claim as new and desire to secure by Letters Patent the following:

1. A circuit selective appliance including electro-magnetic step-by-step operating mechanism, a sluggishly moving circuit controlling element including an unbalanced lever, and a restraining element in the form of a weight normally imposed upon the lighter end of said lever to overcome the action of the heavier end of said lever, thereby normally preventing the operation of said circuit controlling element and removable from influence thereupon by said electro-magnetic mechanism.

2. A circuit selective appliance including a step-by-step actuated switching mechanism, electro-magnetic mechanism for operating the switching mechanism step-by-step, a sluggishly moving circuit controlling element including an unbalanced lever, and a restraining element in the form of a weight normally imposed upon the lighter end of said lever to overcome the action of the heavier end of said lever, thereby normally preventing the operation of said circuit controlling element and removable from influence thereupon by said electro-magnetic mechanism each time said electro-magnetic mechanism is operated to step the switching mechanism.

3. A circuit selective appliance including a step-by-step actuated switching mechanism, electro-magnetic mechanism for operating

the switching mechanism step-by-step, a sluggishly moving circuit controlling element including an unbalanced lever, and a restraining element in the form of a weight normally imposed upon the lighter end of said lever to overcome the action of the heavier end of said lever, thereby permitted by the electro-magnetic mechanism normally to prevent the operation of said circuit controlling element and adapted to be removed from restraining influence upon said circuit controlling element by the operation of the electro-magnetic mechanism.

4. A circuit selective appliance including electro-magnetic step-by-step operating mechanism, a sluggishly moving circuit controlling element, a restraining element normally preventing the operation of said circuit controlling element and removable from influence thereupon by said electro-magnetic mechanism, holding mechanism for maintaining the switching mechanism in the position to which it is stepped, and electro-magnetic mechanism for releasing the holding mechanism and having its circuit governed by the aforesaid circuit controlling element.

5. A circuit selective appliance including a step-by-step actuated switching mechanism, electro-magnetic mechanism for operating the switching mechanism step-by-step, a sluggishly moving circuit controlling element, a restraining element normally preventing the operation of said circuit controlling element and removable from influence thereupon by said electro-magnetic mechanism each time said electro-magnetic mechanism is operated to step the switching mechanism, holding mechanism for maintaining the switching mechanism in the position to which it is stepped, and electro-magnetic mechanism for releasing the holding mechanism and having its circuit governed by the aforesaid circuit controlling element.

6. A circuit selective appliance including a step-by-step actuated switching mechanism, electro-magnetic mechanism for operating the switching mechanism step-by-step, a sluggishly moving circuit controlling element, a restraining element permitted by the electro-magnetic mechanism normally to prevent the operation of said circuit controlling element and adapted to be removed from restraining influence upon said circuit controlling element by the operation of the electro-magnetic mechanism, holding mechanism for maintaining the switching mechanism in the position to which it is stepped, and electro-magnetic mechanism for releasing the holding mechanism and having its circuit governed by the aforesaid circuit controlling element.

7. A circuit selective appliance including electro-magnetic step-by-step operating mechanism, a sluggishly moving circuit con-

trolling element including an unbalanced lever, a restraining element in the form of a weight normally imposed upon the lighter end of said lever to overcome the action of the heavier end of said lever, thereby normally preventing the operation of said circuit controlling element and removable from influence thereupon by said electro-magnetic mechanism; holding mechanism for maintaining the switching mechanism in the position to which it is stepped, and electro-magnetic mechanism for releasing the holding mechanism and having its circuit governed by the aforesaid circuit controlling element.

8. A circuit selective appliance including a step-by-step actuated switching mechanism, electro-magnetic mechanism for operating the switching mechanism step - by - step, a 20 sluggishly moving circuit controlling element including an unbalanced lever, a restraining element in the form of a weight normally imposed upon the lighter end of said lever to overcome the action of the heavier end of 25 said lever, thereby normally preventing the operation of said circuit controlling element and removable from influence thereupon by said electro-magnetic mechanism each time 30 said electro-magnetic mechanism is operated to step the switching mechanism, holding mechanism for maintaining the switching mechanism in the position to which it is stepped, and electro-magnetic mechanism for releasing the holding mechanism and having 35 its circuit governed by the aforesaid circuit controlling element.

9. A circuit selective appliance including a step-by-step actuated switching mechanism, electro-magnetic mechanism for operating the switching mechanism step - by - step, a 40 sluggishly moving circuit controlling element including an unbalanced lever, a restraining element in the form of a weight normally imposed upon the lighter end of said lever to 45 overcome the action of the heavier end of said lever, thereby permitted by the electro-magnetic mechanism normally to prevent the operation of said circuit controlling element and adapted to be removed from 50 restraining influence upon said circuit controlling element by the operation of the electro-magnetic mechanism, holding mechanism for maintaining the switching mechanism in the position to which it is stepped, and 55 electro-magnetic mechanism for releasing the holding mechanism and having its circuit governed by the aforesaid circuit controlling element.

10. A circuit selective system including a 60 transmission conductor, a number of stations, each having a selectable circuit, electro-magnetic step-by-step operating mechanism, a sluggishly moving circuit controlling element, a restraining element normally preventing the operation of said circuit control-

ling element and removable from influence thereupon by said electro-magnetic mechanism, a polarized relay at each of said stations, a switch controlled thereby, a source of current for operating said relays, and a switch for including said relays in circuit with said source of current so as to operate said relays and governing the switch actuating electro-magnetic mechanism.

11. A circuit selective system including a 75 transmission conductor, a number of stations, each having a selectable circuit, step-by-step actuated switching mechanism, electro-magnetic mechanism for operating the switching mechanism step-by-step, a sluggishly moving circuit controlling element, a restraining element normally preventing the operation of said circuit controlling element and removable from influence thereupon by said electro-magnetic mechanism each time 80 said electro-magnetic mechanism is operated to step the switching mechanism, a polarized relay at each of said stations, a switch controlled thereby a source of current for operating said relays, and a switch for including 85 said relays in circuit with said source of current so as to operate said relays and governing the switch actuating electro-magnetic mechanism.

12. A circuit selective system including a 95 transmission conductor, a number of stations, each having a selectable circuit, step-by-step actuated switching mechanism, electro-magnetic mechanism for operating the switching mechanism step-by-step, a sluggishly moving circuit controlling element, a restraining element permitted by the electro-magnetic mechanism normally to prevent the operation of said circuit controlling element and adapted to be removed from 100 restraining influence upon said circuit controlling element by the operation of the electro-magnetic mechanism, a polarized relay at each of said stations, a switch controlled thereby, a source of current for operating 105 said relays, and a switch for including said relays in circuit with said source of current so as to operate said relays and governing the switch actuating electro-magnetic mechanism.

13. A circuit selective system including a transmission conductor, a number of stations, each having a selectable circuit, electro-magnetic step-by-step operating mechanism, a sluggishly moving circuit controlling element including an unbalanced lever, a restraining element in the form of a weight normally imposed upon the lighter end of said lever to overcome the action of the heavier end of said lever, thereby normally 125 preventing the operation of said circuit controlling element and removable from influence thereupon by said electro-magnetic mechanism, a polarized relay at each of said stations, a switch controlled thereby, a 130

- source of current for operating said relays, and a switch for including said relays in circuit with said source of current so as to operate said relays and governing the switch 5 actuating electro-magnetic mechanism.
14. A circuit selective system including a transmission conductor, a number of stations, each having a selectable circuit, step-by-step actuated switching mechanism, electro-magnetic mechanism for operating the switching mechanism step-by-step, a sluggishly moving circuit controlling element including an unbalanced lever, a restraining element in the form of a weight normally imposed upon the lighter end of said lever to overcome the action of the heavier end of said lever, thereby normally preventing the operation of said circuit controlling element and removable from influence thereupon 15 by said electro-magnetic mechanism each time said electro-magnetic mechanism is operated to step the switching mechanism, a polarized relay at each of said stations, a switch controlled thereby, a source of current for operating said relays, and a switch for including said relays in circuit with said source of current so as to operate said relays and governing the switch actuating electro-magnetic mechanism.
15. A circuit selective system including a transmission conductor, a number of stations, each having a selectable circuit, step-by-step actuated switching mechanism, electro-magnetic mechanism for operating the switching mechanism step-by-step, a sluggishly moving circuit controlling element including an unbalanced lever, a restraining element in the form of a weight normally imposed upon the lighter end of said lever to 20 overcome the action of the heavier end of said lever, thereby permitted by the electro-magnetic mechanism normally to prevent the operation of said circuit controlling element and adapted to be removed from restraining influence upon said circuit controlling element by the operation of the electro-magnetic mechanism, a polarized relay at each of said stations, a switch controlled thereby, a source of current for operating 25 said relays, and a switch for including said relays in circuit with said source of current so as to operate said relays and governing the switch actuating electro-magnetic mechanism.
16. A circuit selective system including a transmission conductor, a number of stations, each having a selectable circuit, electro-magnetic step-by-step operating mechanism, a sluggishly moving circuit controlling element, a restraining element normally preventing the operation of said circuit controlling element and removable from influence thereupon by said electro-magnetic mechanism, holding mechanism for maintaining the switching mechanism in the position to which it is stepped, electro-magnetic mechanism for releasing the holding mechanism and having its circuit governed by the aforesaid circuit controlling element, a polarized relay at each of said stations, a switch controlled thereby, a source of current for operating said relays, and a switch for including said relays in circuit with said source of current so as to operate said relays and governing the switch actuating electro-magnetic mechanism.
17. A circuit selective system including a transmission conductor, a number of stations, each having a selectable circuit, step-by-step actuated switching mechanism, electro-magnetic mechanism for operating the switching mechanism step-by-step, a sluggishly moving circuit controlling element, a restraining element normally preventing the operation of said circuit controlling element and removable from influence thereupon by said electro-magnetic mechanism each time said electro-magnetic mechanism is operated to step the switching mechanism, holding mechanism for maintaining the switching mechanism in the position to which it is stepped, electro-magnetic mechanism for releasing the holding mechanism and having its circuit governed by the aforesaid circuit controlling element, a polarized relay at each of 30 said stations, a switch controlled thereby, a source of current for operating said relays, and a switch for including said relays in circuit with said source of current so as to operate said relays and governing the switch actuating electro-magnetic mechanism.
18. A circuit selective system including a transmission conductor, a number of stations, each having a selectable circuit, step-by-step actuated switching mechanism, electro-magnetic mechanism for operating the switching mechanism step-by-step, a sluggishly moving circuit controlling element, a restraining element permitted by the electro-magnetic mechanism normally to prevent the operation of said circuit controlling element and adapted to be removed from restraining influence upon said circuit controlling element by the operation of the electro-magnetic mechanism, holding mechanism for maintaining the switching mechanism in the position to which it is stepped, electro-magnetic mechanism for releasing the holding mechanism and having its circuit governed by the aforesaid circuit controlling element, a polarized relay at each of 35 said stations, a switch controlled thereby, a source of current for operating said relays, and a switch for including said relays in circuit with said source of current so as to operate said relays and governing the switch actuating electro-magnetic mechanism.
19. A circuit selective system including a transmission conductor, a number of stations, each having a selectable circuit, elec-

tro-magnetic step-by-step operating mechanism, a sluggishly moving circuit controlling element including an unbalanced lever, a restraining element in the form of a weight 5 normally imposed upon the lighter end of said lever to overcome the action of the heavier end of said lever, thereby normally preventing the operation of said circuit controlling element and removable from influ-

10 ence thereupon by said electro-magnetic mechanism, holding mechanism for maintaining the switching mechanism in the position to which it is stepped, electro-magnetic mechanism for releasing the holding mechanism and having its circuit governed by the aforesaid circuit controlling element, a polarized relay at each of said stations, a switch controlled thereby, a source of current for operating said relays, and a switch for including said relays in circuit with said source of current so as to operate said relays and governing the switch actuating electro-magnetic mechanism.

20. A circuit selective system including a
25 transmission conductor, a number of stations, each having a selectable circuit, step-by-step actuated switching mechanism, electro-magnetic mechanism for operating the switching mechanism step-by-step, a sluggishly moving circuit controlling element including an unbalanced lever, a restraining element in the form of a weight normally imposed upon the lighter end of said lever to overcome the action of the heavier end of said lever, thereby normally preventing the operation of said circuit controlling element and removable from influence thereupon by said electro-magnetic mechanism each time said electro-magnetic mechanism is operated to
30 step the switching mechanism, holding mechanism for maintaining the switching mechanism in the position to which it is stepped, electro-magnetic mechanism for releasing the holding mechanism and having its circuit governed by the aforesaid circuit controlling element, a polarized relay at each of said stations, a switch controlled thereby, a source of current for operating said relays, and a switch for including said relays in circuit with said
35 source of current so as to operate said relays and governing the switch actuating electro-magnetic mechanism.

21. A circuit selective system including a transmission conductor, a number of stations, each having a selectable circuit, step-by-step actuated switching mechanism, electro-magnetic mechanism for operating the switching mechanism step-by-step, a sluggishly moving circuit controlling element including an unbalanced lever, a restraining element in the form of a weight normally imposed upon the lighter end of said lever to overcome the action of the heavier end of said lever, thereby permitted by the electro-magnetic mechanism normally to prevent the operation of said circuit controlling element and adapted to be removed from restraining influence upon said circuit controlling element by the operation of the electro-magnetic mechanism, holding mechanism for maintaining the switching mechanism in the position to which it is stepped, electro-magnetic mechanism for releasing the holding mechanism and having its circuit governed by the aforesaid circuit controlling element, a polarized relay at each of said stations, a switch controlled thereby, a source of current for operating said relays, and a switch for including said relays in circuit with said source of current so as to operate said relays and governing the switch actuating electro-magnetic mechanism, 55 60 65 70 75 80

22. A circuit selective appliance including electro-magnetic step-by-step operating mechanism, a sluggishly moving circuit controlling element including an unbalanced lever, a restraining element in the form of a weight normally imposed upon the lighter end of said lever to overcome the action of the heavier end of said lever, thereby normally preventing the operation of said circuit controlling element and removable from influence thereupon by said electro-magnetic mechanism, and a holding electro-magneto included in a circuit established by the circuit controlling element and serving to hold said circuit controlling element so as to insure the contact said element causes. 81 90 98

In witness whereof, I hereunto subscribe my name this fifth day of Dec. A. D., 1907.
